United States Patent Office

Des. 189,520
Patented Jan. 3, 1961

189,520

ROBE

Dorothy Jeanne Oakley, Chicago, Ill., assignor to E. R.
Moore Co., Chicago, Ill., a corporation of Illinois

Filed Oct. 20, 1959, Ser. No. 57,995

Term of patent 14 years

(Cl. D3—26)

Fig. 1

fig. 2.

Figure 2 is a rear perspective view thereof.

The essential features of my design reside in those portions shown in full lines on the drawing.

I claim:

The ornamental design for a robe, as shown and described.
